2 SHEETS—SHEET 2.

UNITED STATES PATENT OFFICE.

ROBERT S. LA MERE, OF DRESSER JUNCTION, WISCONSIN.

RAILWAY-SIGNAL.

1,349,773.

Specification of Letters Patent. Patented Aug. 17, 1920.

Application filed December 29, 1919. Serial No. 347,997.

To all whom it may concern:

Be it known that I, ROBERT S. LA MERE, a citizen of the United States of America, residing at Dresser Junction, in the county 5 of Polk and State of Wisconsin, have invented certain new and useful Improvements in Railway-Signals, of which the following is a specification.

My present invention relates generally to 10 signals and more particularly to railway crossing signals, my object being the provision of a mechanical train actuated signal for highways which will be unfailing and efficient in its operation to warn of the 15 approach of trains.

A further object is the provision of a signal which will be set by the approach of a train and which will be released by the 20 train only after its passage across the highway.

A still further object is the provision of an arrangement which will eliminate electrical and other connections likely to fail in warning under adverse weather conditions, and whose nature is such that it may 25 be readily maintained in effectively operating condition at all times.

In the accompanying drawings which 30 illustrate the best mode I have so far devised for carrying out the invention,

Figure 1 is an elevation illustrating the practical application of my invention,

Fig. 2 is a top plan view of the train actuated signal setting arrangement,

Fig. 3 is a similar view of the train actuated signal releasing mechanism, and

Fig. 4 is an enlarged vertical section through the signal post and signal mechanism supported thereby.

Referring now to these figures and particularly to Figs. 1 and 4 my invention proposes the use of an upright signal post 10 on highways at or adjacent to railway crossings, provided at a point suitably elevated 45 above the highway surface with a pair of laterally extending downwardly inclined boxes 11 which open upwardly to receive a pair of signal arms 12 in their lower inactive positions whereby to conceal the same.

As seen particularly in Fig. 4, the post 10 has a vertical axial opening communicating at its upper end with slotted side openings in which the inner portions of the signal arms 12 are pivoted at 13, these arms being 55 simultaneously swingable upon their pivots from the upper active position of Fig. 1

to the lower inactive position of Fig. 4 by virtue of their pivotal connection at their extreme inner ends with the upper end of a signal rod 14.

The rod 14 depends through the axial opening 15 of the post and into the lower enlarged base or foundation 16, in which the signal rod shifting parts are located. In this lower enlarged base of the post the 65 lower end of the signal rod 14 has a roller 17 at its lower extremity engaging a clover shaped cam 18 at one side of an enlarged gear wheel 19 and rotatable therewith. This cam has at the extremity at each of its projections a concave seat 20 in which the roller 17 is engaged when the rod 14 is in its lowermost position and the signal arms 12 are in active position as in Fig. 1.

The gear wheel 19 with its cam 18 is 75 mounted upon a shaft 21 which also forms the fulcrum of a pair of operating levers 22 and 23, each having adjacent to one end a spring controlled dog 24 in engagement with the teeth of gear wheel 19. By reference to Fig. 4 particularly, it will be noted that the dogs 24 of the two levers engage the gear wheel at relatively opposite sides thereof to shift the gear in the same direction, and that the opposite ends of the 80 two levers 22 and 23 are pivotally connected to the upper ends of vertical connecting rods 25 and 26 so that when the rod 25 for instance is lowered from the position shown in Fig. 4 the gear wheel 19 will be rotated 90 in the direction of the arrow by virtue of the rocking of lever 22 on its fulcrum. During the rotation of the gear wheel with its cam 18, the latter will force the roller carrying the lower end of the signal rod 95 14 downwardly until it comes to rest in the adjacent concave seat 20 of the cam at the end of the operative stroke of lever 22 and it will be observed that when the connecting rod 25 is released the lever 22 returns to the 100 position of Fig. 4, the dog 24 of the other lever 23 will act to avoid movement of the gear wheel in the opposite direction. When this movement has taken place the signal arms 12 will be elevated in the active position shown in Fig. 1, exposed to view on the highway above the boxes 11. When, 105 subsequent to the foregoing movement, the connecting rod 26 is elevated, lever 23 will be rocked on its fulcrum and a second partial rotative movement will be imparted to the gear wheel 19 in the same direction,

shifting roller 17 out of the concave seat it formerly occupied so that the rod 14 will move upwardly by the weight of the signal arms 12 as the roller 17 shifts to a position 5 between two of the cam projections. It is obvious that when the rod 26 is released, the dog 24 of lever 22 will act to prevent rotation of the gear wheel in a reverse direction as lever 23 shifts back to its normal 10 position shown in Fig. 4.

Referring now to Fig. 2, the vertical connecting rod 25 depends from the lever 22 and is connected at its lower end to one arm of a bell crank lever 27, the other arm of 15 which is connected to a horizontal connecting rod 28 which passes along one side of the track rails 29 and is pivotally connected at its outer end to a second bell crank lever 30. This bell crank lever 30 is connected by a 20 rod 31 with a laterally yieldable actuating bar 32 disposed along the inner face of one of the track rails and provided with bent ends 33 turned away from the rail. Bar 32 is yieldingly held by spring 34 and is thus 25 shiftable by the flange of a car wheel to rock the bell crank 30 and, through the connecting rod 28 also rock the bell crank 27 in order to effect downward movement of the vertical connecting rod 25, bar 32 being 30 greater in length than the space between the car wheels of a train.

By reference to Fig. 3 it will be noted that the apparatus of Fig. 2 is duplicated upon the opposite side of the highway crossing, 35 vertical connecting rod 26 of the lever 22 being connected to a bell crank 35 and, through connecting rod 36 to a second bell crank 37, the latter of which is connected by a rod 38 to a yieldable rail carried actuating 40 bar 39 similarly constructed and mounted as previously described with respect to the bar 32.

In this way following the description of the operation previously given it is obvious 45 the signal can be set by the approach of a train in either direction and that my invention thus readily lends itself to single or double track systems and operates to positively set and release the signal arms when 50 the train respectively approaches the crossing and after it has passed over a crossing.

It will also be noted that the structure described both as to primary movable parts and their connections, readily lends itself to the incasing or boxing of these parts and connections in order to entirely avoid danger of their improper operation or of their being adversely effected by weather conditions or other exterior influences.

60 As will be seen in Figs. 2 and 3 the horizontal connecting rods preferably have springs 41 which supplement the action of the springs of actuating bars so that when a train has passed, during which the respective

vertical bar is drawn downward, the springs 65 will act to elevate the vertical connecting bar and return respectively the gear actuating lever to normal position.

I claim:

1. A railway crossing signal including 70 track carried actuating devices, a signal post, a signal arm, a signal rod movable vertically in the post and connected to said arm, a gear wheel having a cam controlling movement of said rod, a pair of levers fulcrumed at the center of said gear wheel and provided at one end with spring controlled dogs engaging the gear wheel at opposite sides thereof to rotate the same in similar directions, and connecting rods leading from the 75 actuating devices to said levers for moving the latter.

2. A railway crossing signal including 80 track carried actuating devices, a signal post, a signal arm, a signal rod movable vertically in the post and connected to said arm, a gear wheel having a cam controlling movement of said rod, a pair of levers fulcrumed at the center of said gear wheel and provided at one end with spring controlled dogs engaging the gear wheel at opposite sides 85 thereof to rotate the same in similar directions, and connecting rods leading from the actuating devices to said levers for moving the latter, said cam having projections provided with concave seats at their ends, and said signal rod having a cam engaging roller seated in one of said seats when the signal arm is in active position.

3. A railway crossing signal including 90 track carried actuating devices, a signal post, a signal arm, a signal rod movable vertically in the post and connected to said arm, a gear wheel having a cam controlling movement of said rod, a pair of levers fulcrumed at the center of said gear wheel and provided at one end with spring controlled dogs engaging the gear wheel at opposite sides 95 thereof to rotate the same in similar directions, and connecting rods leading from the actuating devices to said levers for moving the latter, said post having a vertical opening 100 for the signal rod and an enlarged base housing the gear wheel and its operating parts.

4. A railway crossing signal including a 105 vertically movable signal arm, a signal post carrying the arm, a signal rod connected to the arm, a rotating member for controlling movement of said rod by its rotation continuously in one direction, a pair of levers having dogs for engaging and rotating said member in one direction, and a pair of actuating mechanisms, each connected to one 110 of said levers, as described.

In testimony whereof I affix my signature.

ROBERT S. LA MERE.
